MEAT TENDERIZING DEVICE OR SIMILAR ARTICLE

Rene Kyburz, Hamburg, and Andre P. Jaccard, Buffalo, N.Y., assignors to Jaccard Corporation, Buffalo, N.Y., a corporation of New York

Filed Dec. 28, 1967, Ser. No. 9,954

Term of patent 14 years

(Cl. D11—1)

FIG. 1 is a front elevational view of a meat tenderizing device or similar article showing our new design.

FIG. 2 is a rear elevational view thereof.

FIG. 3 is a view taken from the right side of FIG. 1; the opposite side view being substantially the same.

FIG. 4 is a top plan view thereof.

FIG. 5 is a bottom plan view thereof.

The characteristic features of our design reside in the portions shown in full lines.

We claim:

The ornamental design for a meat tenderizing device or similar article, substantially as shown and described.
